UNITED STATES PATENT OFFICE

FRANK M. PRESTWICH, OF NEW YORK, N. Y.

BLINDSTITCH-SEWING MACHINE

Application filed August 9, 1926. Serial No. 128,013.

This invention relates to blind stitch sewing machines, and has for its object to provide a machine which is capable of working upon a wide variety of materials including both fine and thick fabrics, as well as materials of a non-uniform thickness.

A well known form of blind stitch machine comprises a curved needle movable through the under fabric and then diagonally through the overlying material with a fabric bender located beneath the goods and adapted to raise the goods into co-operation with the needle. An objection to this type of machine is the inability to satisfactorily operate upon materials of non-uniform thickness, such as a coat sleeve lining at the arm hole which has more padding in one part than in another, also the top of waistbands of trousers where belt loops and buttons are encountered. With the bender located beneath the material, set to give a predetermined thrust, a larger protrusion or dome is formed with thick material than with thin, and therefore since the diameter of protrusion with thick material is greater than with thin, the needle has a longer stroke through the goods, with the result that it may be too great to form a proper or even stitch if the material is of non-uniform thickness.

According to this invention, a picker is provided instead of the bender of the prior art, and the picker is located to penetrate the lower fabric top and move it in timed relation to the needle for penetration thereby precisely as the first movement in hand sewing. Since the picker enters the top of the material, in the vicinity of the path of the needle, it makes little or no difference whether the work be thick or thin, or of varying thickness, for the bottom face of the stationary foot forms the definite line for the material to be sewn. A yieldable work support is provided to take care of larger irregularities in thickness of work and the top surface of work support may be made flexible to take care of sudden minor irregularities in work thickness. This yieldable work support will press the work evenly against the front and back of the foot regardless of varying thickness of work and the top surface of the work

will at all times be on a definite line between front and back surface of the foot and in precisely the correct register for the picker needle to strike through the opening in the foot. The movement of the picker is adjustable for different conditions, to obtain different lengths and depths of thrust. The machine of this invention has a greater field of usefulness than prior art machines now commercially used as it is adaptable for use with heavy overcoats or with the hemming at the bottom of a thin satin skirt.

Referring to the drawings:

Fig. 1 is an elevation partly in section of a blind stitch sewing machine embodying this invention,

Fig. 2 is a left end view of the device of Fig. 1,

Fig. 3 is a section on the line *c-c* of Fig. 1.

Fig. 4 is a section on the line *d-d* of Fig. 1.

Fig. 5 is a section on the line *e-e* of Fig. 1.

Fig. 6 is a section on the line *f-f* of Fig. 1.

Fig. 7 illustrates the form of machine in which the picker needle does not move back and forward with the feed dog.

Fig. 8 is a longitudinal section of the work support on line *h-h* shown in Fig. 7.

Fig. 9 shows another type of work support.

Fig. 10 is a top plan view of yet another construction for the work support.

Fig. 11 is a longitudinal section of the work support of Fig. 10 on line *g-g* thereof.

Fig. 12 is a view corresponding to Fig. 6, but of a modified construction.

Fig. 13 is a rear view of the device of Fig. 12.

Fig. 14 is a rear view of the device of Fig. 12 with the sewing needle removed.

As is customary in blind stitch sewing machines, the power is supplied to the shaft 10, transmitted through the member 12, connecting rod 11 and crank 13 to the needle 15 mounted in the bearing 14. Any suitable stitch forming mechanism will be used, and same is not shown herein, since a looper or shuttle can be used as desired. The usual mechanism is provided within the casing 16 for turning the needle support 17 and bearing 14, so that the needle 15 moves alternately parallel and at an angle to the movement of 100

the work passing beneath the presser foot 18 hung from the depending support 19. According to common practice, the presser foot is recessed to permit a feed dog to engage the work, and is also provided with a usual edge guide and projection for raising the edge of the work. Beneath the presser foot is the work support 20 shown in Fig. 1, being pivotally mounted on the rod 21 through the supporting column 22 through which passes the pin 23 for transversely pivoting the frame 24 for the yieldable work support 26, which is rotatable in the bearings 25 of said frame. As shown in Figs. 1 and 5, the yieldable work support 26 comprises resilient prongs 27 and 28 extending alternately from opposite sides of the rotatable member 26. In this way, irregularities in thickness of the work passing over the top central portion of the resilient work support 26 may be compensated for by bending of the prongs 27 and 28.

Larger irregularities may be taken care of by yielding of the supporting member 29 against the action of spring 30. Owing to the pivotal mounting of the yieldable work support 26, the member 26 as a whole may tilt to compensate for the presence of irregularities in thickness of the work transversely of the path of movement of the work through the machine. The plate 31 shown in Figs. 1 and 5 is provided with a large recess through which the yieldable work support 26 co-operates with the work.

Also mounted on the shaft 10 is the gear 32 engaging another gear 33 on shaft 34 driving the bevel gear 35 and its co-operating bevel gear on the shaft 36. As shown in Fig. 3 the bevel gear 35 is blanked throughout a portion of its circumference so as to only intermittently actuate the shaft 36 in timed relation to the movement of the main shaft 10 and needle 15. On the lower end of shaft 36 is another bevel gear 37 actuating the co-operating gear 38 on shaft 39 within the bearing 40 for driving the rotatable member 41 provided with a slot 42 as shown in Figs. 1 and 6. Adjustably mounted within this slot 42 is the pin 43 passing through one end of the connecting bar 44 having the picker needle 45 mounted at its other end. This picker needle is so located and actuated as to engage the work in timed relation to movement of the needle 15 and move the work to sufficient height to be engaged by the needle 15. Within the connecting bar 44 is the slot 46 having the pivot pin 47 passing therethrough and on which the connecting bar 44 is mounted. The pivot pin 47 is slidable within its supporting bearing in bracket 48 with the backward and forward movement of the feed dog. A wing nut 49 adjustably controls the height of the bracket 48 which is slotted at 50 for this purpose. The feed dog 53 has an extension 52 provided with bifurcated ends 51 engaging a threaded member on the pivot pin 47 for

giving this pin and likewise the picker needle 45 a forward and backward movement with the feed dog. Simultaneously member 41 raises and lowers the picker needle in properly timed relation to the movement of the stitching needle 15, so that the picker needle has both up and down movement and backward and forward movement. As shown in Fig. 5 the presser foot is recessed to enable the picker needle 45 to co-operate with the work. Also in Fig. 5 alternate parallel and angular movements of the stitching needle 15 are represented by the dotted lines 54. The feed dog as is customary is actuated by a pair of eccentrics shown in Fig. 1 on shaft 10, one for giving it the forward and backward movement, the other the up and down motion. For controlling the angular relationship between gear 33 and shaft 34 for accurately timing the picker needle, the shaft 34 is provided with the projection 55 thereon, and secured to the gear 33 are the projections 56. Adjustable threaded members pass through the projections 56 and engage the projection 55 enabling the shaft to be relatively rotated a slight amount with respect to the gear 33, the gear 33 being otherwise free on the shaft and driving the shaft 34 through projections 55 and 56, as shown in Fig. 6.

Fig. 7 illustrates the preferred embodiment of this invention, in which the picker needle does not have the forward and backward movement with the feed dog; that is, there is no extension on the feed dog as in the preceding figure, but the picker needle here does have its movement laterally in the path of the goods as previously described in timed relation to the stitching needle 15. In other words, in Fig. 7 the picker needle has the same function as in the previously described embodiment of this invention, except that it does not move backward and forward with the feed dog, but only has the rotary movement referred to.

Figs. 12 to 14 inclusive illustrate other views of the same preferred form of the invention that is shown in Fig. 7.

The work support shown in Figs. 7 and 8 comprises the recessed plate 65, mounted on the supporting column 58 which is yieldable under the action of spring 64 to take care of large irregularities in thickness of the work. The springs 66, mounted on the cross bars, illustrated pass through the recess in plate 65 and enable small irregularities in thickness of the work to be taken care of.

Fig. 9 illustrates a type of work support in which the plate 62 is not recessed and is yieldable only under the action of the spring 63.

Fig. 10 shows another form of work support in which the plate 57 is recessed and the springs 60 constitute individually yieldable support members within the recess to take up irregularities in the thickness of the work.

work, such as belt loops or buttons in sewing trouser waistbands. Also, the tautness of the work throws extra thicknesses into the space between. Each of the springs 60 is of general spiral shape as shown. Larger variations in thickness of the work are compensated for by the spring 59, shown in Fig. 11.

Among the advantages of this invention may be mentioned the ability of the machine to operate on a wide variety of work, whether thin goods or thick material and with equal facility. The picker needle may engage the work at the side or on substantially its upper surface, so as to move either thin or thick material with equal ease. A special advantage of this machine is its adaptability to produce better work through having the stitches uniform when the work varies in thickness, as for example, in the upper attachment of the lining of a coat sleeve where the goods are not of uniform thickness due to more padding being used in some portions of the shoulder than in others. By loosening the nuts on shafts 43 and 47, the bar 44 can be moved backward or forward to vary the eccentricity of shaft or pin 43 with respect to the rotatable disc or wheel 41. This variation will naturally change the length of the stroke of the picker needle 45. By loosening the wing nut 49 and moving the bracket plate 48 upward or downward the average height of the picker needle and the bar 44 can be varied. After the proper eccentricity of shaft 43 has been achieved and the bracket plate 48 has been moved to the desired height, the nut on shafts 43 and 47 can be tightened as well as the wing nut 49. The bar 44 naturally will have a certain amount of movement with respect to the shaft 47, but the shaft 47 does act as a fulcrum for the bar 44. The different types of yieldable work supports shown enable the goods to be passed under the presser foot without interfering with the operation of the machine, and the location of the picker needle above the presser foot or feeding means enables the work support to be constructed to take care of both small variations in thickness as well as large. The helical spring in the work support facilitates the entry of the work into the machine. An advantage of this invention resides in doing away with the necessity of any mechanism in the lower part of the machine to operate on the work so that the space around the work support may be of any design to suit any particular work.

Provision may be made for using a picker needle to penetrate the top layer of the lining at every stitch if desired.

60 I claim:

1. In a blind stitch sewing machine, the combination with a work support and means for feeding two layers of material through the machine, of a picker for penetrating the superimposed layer and the upper surface of

the base layer of the material and moving both to a predetermined position, a curved needle positioned to similarly penetrate the layers and form the stitch when the layers are so moved by the picker and means for driving the feeding means, picker and needle in synchronism.

2. In a blind stitch sewing machine, the combination with a work support, a presser foot spaced therefrom to permit the passage of two layers of material, and feeding means, of a picker for penetrating the superimposed layer and the upper surface of the base layer of the material and moving both to a predetermined position, a curved needle positioned to similarly penetrate the layers and form the stitch when the layers are so moved by the picker, and means for driving the feeding means, picker and needle in synchronism.

3. In a blind stitch sewing machine, the combination with a work support, a presser foot spaced therefrom to permit the passage of two layers of material, and feeding means, of a picker for penetrating the superimposed layers and the upper surface of the base layer of the material and lifting both from the work support to a predetermined position, a curved needle positioned to similarly penetrate the layers and form the stitch when the layers are so lifted by the picker, and means for driving the feeding means, picker and needle in synchronism.

4. In a blind stitch sewing machine, the combination with a work support, of means for feeding the work through the machine, a needle, means for actuating the needle alternately parallel and at an angle to the movement of the work, a picker needle located adjacent the first needle and above the work support, means for actuating the picker needle in timed relation to the first needle for penetrating and moving the work into the path of the first needle, and means to control the amount of material moved by the picker needle.

5. In a blind stitch sewing machine, the combination with a work support, means for feeding the work through the machine, a needle, and means for actuating the needle alternately parallel and at an angle to the movement of the work, of a picker needle located adjacent the first needle and above the work support, and means for actuating the picker needle in timed relation with the first needle for penetrating and moving the work into the path of the first needle.

6. A blind stitch sewing machine comprising a work support, means for feeding two layers of material through the machine, picker means located above the work support for penetrating the superimposed layer and the upper surface of the base layer of the material and lifting both from the work support, a curved needle positioned to similarly penetrate the layers to form the stitch when

the layers are so lifted by the picker, a yieldable work engaging member supported in said work support and means for driving the feeding means, picker means and needle in synchronism.

5 7. A blind stitch sewing machine comprising a needle, actuating mechanism therefor, a work support, means for feeding the work over the work support, picker means operated in timed relation to said needle to penetrate and move the work into the path of the needle, said work support comprising a flexible member for yielding under small irregularities in thickness of the work, and a yieldable support for said flexible member whereby larger irregularities in thickness of the work are provided for.

20 8. A blind stitch sewing machine comprising a needle, actuating mechanism therefor, a work support, means for feeding the work through the support, picker means located above the work and actuated in timed relation to the needle for penetrating and moving the work for engagement by said needle, said work support comprising a flexible member for bending under small irregularities in thickness of the work, and a yieldable support for said flexible member whereby larger irregularities in thickness are provided for.

25 9. In a blind stitch sewing machine, the combination with a work support, of means for feeding work through the machine, a needle, means for actuating the needle, a picker needle located adjacent to the first needle and above the work support, means for actuating the picker needle in timed relation to the first needle for penetrating and moving the work into the path of the first 40 needle and means for adjusting the movement of said picker needle.

10. In a blind stitch sewing machine, the combination with means for feeding the work therethrough, of a needle, actuating mechanism therefor, means timed with the needle for penetrating the work above its lower surface and moving the work to intercept the needle and a yieldable work support beneath said needle.

50 Signed at New York in the county of New York and State of New York this 2nd day of August, A. D. 1925.

FRANK M. PRESTWICH.
